UNITED STATES PATENT OFFICE.

JULIUS S. GARFINKLE, OF NEW YORK, N. Y.

DESIGN FOR AN ELECTRIC-FIXTURE ARM.

60,231.

Specification for Design.

Patented Jan. 17, 1922.

Application filed April 11, 1921. Serial No. 460,516. Term of patent 7 years.

To all whom it may concern:

Be it known that I, JULIUS S. GARFINKLE, a citizen of the United States, and a resident of the city of New York, borough of Manhattan, in the county of New York and State of New York, have invented a new, original, and ornamental Design for an Electric-Fixture Arm, of which the following is a specification, reference being had to the accompanying drawing, forming part thereof.

In the accompanying drawing:

Figure 1 is a plan view of an electric fixture-arm, showing my new design.

Figure 2 is a side view.

I claim:

The ornamental design for an electric fixture-arm, as shown.

JULIUS S. GARFINKLE.
